(57) **CLAIM**

The ornamental design for a cell phone holder as shown and described.

DESCRIPTION

FIG. 1 is an upper perspective view of a cell phone holder showing my new design.

FIG. 2 is a front elevation view thereof;

FIG. 3 is a rear elevation view thereof;

FIG. 4 is a side view thereof;

FIG. 5 is an opposite side view thereof;

FIG. 6 is a top plan view thereof;

FIG. 7 is a bottom plan view thereof;

FIG. 8 is a perspective view of the cell phone holder of FIG. 1 shown in an environment of use; and,

FIG. 9 is another perspective view of the cell phone holder of FIG. 1 shown in environment of use.

Broken lines and adjacent unshaded surfaces illustrate portions of the cell phone holder that form no part of the claimed design. Additional broken lines in FIGS. 8 and 9 illustrate environmental subject matter that forms no part of the claimed design.

1 Claim, 6 Drawing Sheets
